CAM OPERATED CIRCUIT BREAKER

Clair D. Lake, Binghamton, and Michael Fiehl, Endicott, N. Y., assignors to International Business Machines Corporation, New York, N. Y., a corporation of New York

Application October 11, 1946, Serial No. 702,756

3 Claims. (Cl. 200—153)

1

This invention relates to electrical circuit breakers, and particularly to cam operated contacts for making and breaking an electrical circuit.

More specifically, this invention pertains to cam operated, electrical circuit breakers for use in high speed electrical accounting machines wherein a plurality of such devices is operated by a common cam shaft.

It is well known that when a pair of electrical contacts is opened and closed with great rapidity a tendency exists for the contacts to vibrate or to oscillate. It is also well known that this tendency, sometimes referred to as "contact bounce," is more prevalent where a pair of contacts is biased under spring tension which is a means frequently used for holding contacts normally closed or normally open. A common method for reducing contact bounce between contacts of this type is by increasing the size or the tension of the spring which biases the contacts; however, as the size or tension of the spring is increased limitations are reached, especially in devices such as high speed electrical accounting machines.

It is a common practice in electrical accounting machines to pass record cards between a plurality of sensing contacts or brushes and a contact roller whereby a perforation in a card is sensed when a brush makes electrical contact with the roller through the perforation when it occurs. Since the current flowing in such a circuit frequently reaches a value not capable of being properly interrupted by the brush and contact roller, circuit breakers are normally included in the circuit. These circuit breakers are adjusted to close the circuit after the brush contacts the roller and to open the circuit before the brush breaks contact with the roller. Consequently, it is essential that a circuit breaker so employed is free from "contact bounce" otherwise the purpose of its inclusion is defeated. As the speed of operation of an electrical accounting machine becomes higher and higher as a result of technical improvements it is even more essential that the circuit breaker components maintain proper circuit continuity.

It is, accordingly, an object of this invention to provide improved means for making and breaking an electrical circuit with great rapidity and maximum reliability.

It is a further object of this invention to provide a cam operated, electrical circuit breaker of improved construction and arrangement of parts whereby tendencies for its contacts to vi-

2

brate or to oscillate during high speed operation are eliminated.

Other objects of the invention will be pointed out in the following description and claims and illustrated in the accompanying drawings, which disclose, by way of example, the principle of the invention and the best mode, which has been contemplated, of applying that principle.

In the drawing:

Fig. 1 is a front elevation view of the circuit breaker having a cut away portion and a fragmentary view of a coacting actuating cam.

Fig. 2 is a fragmentary view of Fig. 1 illustrating the operation of the circuit breaker.

Fig. 3 is a fragmentary view of Fig. 1 illustrating further the operation of the circuit breaker.

With reference to the drawing, a rocker arm 10 is pivotally connected with an insulating contact supporting block 11 by way of a shaft 12 and a bearing 13. The block 11 is slotted to permit the rocker arm 10 to be partially contained within it. One end of the rocker arm 10 is provided with a shaped nose 14 which is biased by a spring 15 normally to urge the nose 14 upwards to contact an actuating cam 16 mounted on a shaft 17 which rotates in a clockwise direction. The spring 15 is contained in recessed wells respectively in the arm 10 and the block 11 and also tends to rotate the arm 10 in a clockwise direction. On the other end of the arm 10 is fastened an operating lug 18 by means of an insulating strip 19 which is pinned respectively to the arm 10 and the lug 18 by the pins 20.

Recessed partially in the block 11 and secured to the block by the screws 21 is a contact holder 22 containing a slideable plunger 23 having a contact 24 at one end. The opposite end of the plunger 23 is hollowed to contain spring 25 which continually urges the plunger 23 to the left as viewed in Fig. 1. A notch 26 is cut into the plunger 23. The lug 18 is arranged to engage the notch 26 so that a counterclockwise rotation of the arm 10 will cause the plunger 23 to be moved to the right (as seen in Fig. 1) and the spring 25 to be compressed. Another contact holder 27 is partially recessed in the block 11 and secured to the block by a screw 28. A fixed contact 29 is inserted in a hole in the holder 27 and is retained by set screw 30. The fixed contact 29 is arranged to be coaxial with the contact 24 and the plunger 23, the last two mentioned components forming the movable contact of the circuit breaker. Tapered sockets 31 are provided in both the holder 22 and the holder 27 for attaching wires or cables. The

block 11 is provided with mounting holes 32 by which the circuit breaker can be attached.

The nose 14 of the rocker arm 10 is provided with a flat angle surface 14a, the degree of angularity being critical and is determined experimentally, depending upon the speed at which the circuit breaker is to be operated. The lug 18 and the notch 26 are so constructed to provide a certain amount of play between them, the amount of play being critical and is determined experimentally, depending upon the speed at which the circuit breaker is to be operated.

Operation of the present invention can be understood by reference to Fig. 1 of the drawing where the circuit breaker is shown with its movable contact held open by the lug 18 due to the point of the nose 14 of the arm 10 riding on the face of the cam 16. The plunger 23 is at this time held in its extreme right hand position, and the springs 15 and 25 are compressed. As the cam 16 rotates clockwise the nose 14 of the arm 10 rides along the cam face until a condition is obtained as in Fig. 2. At that time the point of the nose 14 drops off the cam 16 and the face 14a maintains contact with the cam, the arm 10 rotating clockwise so that the lug 18 permits the plunger 23 to be moved to the left urged by the tension in the spring 25 to close the contact 24 against the contact 29. The lug 18 bears against the right side of the notch 26 when the contacts close.

Following the law of reaction the maximum tendency for "contact bounce" in a pair of closing contacts occurs when the contacts impinge or shortly thereafter. In the present invention these tendencies are counteracted by a further operation of the circuit breaker as follows:

When contact 24 impinges against contact 29 the face 14a contacts the receding lobe of cam 16. An instant later (see Fig. 3) all contact between the cam 16 and the arm 10 is severed as the cam continues to rotate. Arm 10 rotates clockwise under the urging of the spring 15 until lug 18 travels to the left finally being arrested by encountering the left side of the notch 26. Consequently any tendency for the plunger 23 to react or to bounce to the right as a result of impinging its contact 24 against the fixed contact 29 is compensated. As hereinbefore stated, the angularity of the face 14a and the size of the notch 26 are determined before hand and so arranged to secure the desired effect commensurate with the speed of operation of the circuit breaker. Minor adjustments are obtained by adjustment of the fixed contact 29 which can be held in various fixed positions by means of the set screw 30.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A circuit controlling device comprising a relatively stationary contact, a contact movable toward the stationary contact into engagement therewith, a spring urging the movable contact into engagement with the stationary contact, a rotatable cam, a pivoted follower for the cam, said

follower having a first portion engaged with the movable contact so as to have play between them and a second portion engaged with the cam so as to restrain movement of the movable contact toward the stationary contact while bearing against the operating face of the cam, a second spring urging the said second portion toward the said cam and the said first portion to take up play between it and the said movable contact, the said cam having an abrupt drop for releasing the follower to allow the movable contact to move into engagement with the stationary contact under influence of the first mentioned spring, the said second portion of the follower being shaped to so coat with the cam at its drop shoulder as to produce a graduated release of the follower from the operating face of the cam thereby delaying the action of the second said spring for taking up of the said play between the said first portion and the movable contact until it has fully engaged the said stationary contact to compensate for rebounding of the said contacts.

2. In a cam operated electrical circuit breaker, a stationary contact and a movable contact operable to engage the stationary contact, a pivoted cam follower for operating the said movable contact, the said follower having two arms, the first arm engaging the said movable contact and the second arm engaging the said cam to restrain the movable contact from engagement with the stationary contact until a drop in the cam occurs, a first resilient means associated with the movable contact biasing it to engage the stationary contact, a second resilient means associated with the said second arm biasing the said follower to operate to engage the said movable contact with the said stationary contact, and the said second arm arranged to effect release of the said follower from the said cam when a drop occurs so that the movable contact engages the stationary contact under the influence of the said first resilient means and then under the influence of the combined said first and second resilient means whereby tendencies for the said contacts to disengage are eliminated.

3. Circuit controlling apparatus comprising an insulated support having a slotted portion, a rocker arm within the slotted portion pivotally mounted to the said support, a rotatable cam shaft having attached thereto a cam arranged with an abrupt drop, a holder on the said support provided to receive a contact, a contact fitted into the said holder, means for fixing the said contact in the said holder in one of several positions, a second holder on the said support to receive a cylindrical plunger, a notched plunger mounted slidably in the said second holder, a contact on one end of the said plunger capable of engaging the fixed contact, a spring coacting with the other end of the said plunger and the said second holder to bias the plunger contact into engagement with the said fixed contact, one end of the said rocker arm engaging with play the said plunger at the said notched portion and another end of the said rocker arm engaging the said cam in such a manner as to restrain the said plunger contact from engagement with the said fixed contact until the said shaft rotates the said cam to present the said drop, a second spring associated with the said rocker arm to augment the plunger spring, and an angular face upon the second mentioned end of the said arm arranged when acted upon by the said cam at its drop to release the said arm gradually from the said cam until the said plunger contact engages the said fixed con-

tact under the influence of the said plunger spring and thereafter to release the said arm abruptly from the said cam so that the said second spring takes up the said play at the notched portion of the said plunger to counteract rebound tendencies of the said contacts.
